UNITED STATES PATENT OFFICE.

JOSEPH T. BENDER, OF NEWARK, NEW JERSEY.

CUFF-HOLDER.

SPECIFICATION forming part of Letters Patent No. 392,401, dated November 6, 1888.

Application filed March 24, 1888. Serial No. 268,357. (No model.)

To all whom it may concern:

Be it known that I, JOSEPH T. BENDER, a citizen of the United States, residing at Newark, in the county of Essex and State of New Jersey, have invented certain new and useful Improvements in Ladies' Cuff-Holders; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention is designed to provide a simple and effective and also a cheaply-constructed device for holding women's cuffs within the dress-sleeve in lieu of the annoying method usually employed of pinning the cuff to the sleeve.

The invention consists, essentially, of two pairs of clamping-jaws connected together and arranged at right angles to each other, the purpose of which arrangement will be set forth more particularly hereinafter, said jaws being formed from an integral piece of metal and made by turning over the ends thereof, substantially as illustrated in the drawings.

In the drawings herewith accompanying, in which similar letters of reference are employed to indicate like parts in each of the different views, Figure 1 is a perspective view of a cuff and a portion of a sleeve within which the same is secured by my improved holder. Fig. 2 is a perspective view of my improvement detached from the cuff and sleeve. Fig. 3 is a plan view of the same and the cuff and sleeve, which are indicated by dotted lines. Fig. 4 is a section through the cuff and sleeve and side elevation of the holding device, looking in the direction of the arrow numbered 1 on Fig. 3. Fig. 5 is an elevation of the holder, looking in the direction of the arrow numbered 2 on Fig. 3. Fig. 6 is a plan of my improved holder. Fig. 7 is a section of the same, taken through line x; and Figs. 8 and 9 are plan views of different forms of blanks from which my improved holder is made.

As indicated in said above-described views, the holder is composed of two pairs of clamping-jaws formed by bending over the ends of the metallic blank, between which the edges of the cuff and the sleeve are held, and as said

pairs of jaws are connected together the cuffs are retained within the sleeves. One of said pairs of jaws clamps one of the overlapping edges of the cuff and the other pair of jaws seizes the edge of the sleeve of the dress, substantially as indicated in Figs. 3 and 4. The pair of jaws which seizes the cuff may be applied to any part of the edge thereof, so that the cuff can be projected from the sleeve any desired distance.

As shown in the figures of the drawings, the cuff-holder consists of the clamping-jaws a and a', which seize the cuff C, and the jaws b and b', between which the edge of the sleeve S is held. The entire cuff-holder is made from one piece of spring metal, the jaws being formed by bending over the ends of the blank from which the holder is formed. As shown in the views the pair of jaws a and a' and b and b' are arranged at right angles, one to the other, so that when the pair of jaws which seizes the edge of the cuff is in wearing position on the cuff the second pair of jaws is in position to receive and clamp the edge of the sleeve, substantially as shown in Fig. 3. Teeth a² and a³ are formed on the jaws a and a', and the jaws b and b' are also provided with teeth b² to enable the said pairs of jaws to retain their hold upon the cuff and sleeve. In lieu of the teeth a rounded projection, b³, may be formed on the jaw b', as indicated in Figs. 6 and 7, which is preferable with certain goods. However, the form, number, and arrangement of the teeth or holding devices may be greatly varied without departing from the central idea of my invention. Each pair of jaws may be made exactly alike, so that either pair can be used to hold either the cuff or sleeve, as may be desired. This feature is of considerable importance, as it avoids the necessity of using right and left holders, and thereby simplifies the making thereof and also the adjustment of the same in wearing position. The upper portion, b', of the jaws which seize the sleeve may be ornamented, as desired.

In the figures of the drawings the jaws are shown as standing apart to more clearly illustrate the same, but when detached from the cuff the jaws should touch or approach each other, so as to exert holding-power when separated by the material of the cuff or sleeve.

When in wearing position, the cuff can be

detached from the sleeve simply by lifting the upper portions of the jaws which seize the sleeve and drawing off the cuff, the holder remaining attached to the cuff as long as it is intended to be worn.

Having thus described my invention, what I claim is—

A cuff-holder composed of jaws a a' and b b' , formed of the bent-over ends of an integral piece of spring metal at right angles one to

the other, said jaws being provided with holding-teeth struck up from the same, for the purposes set forth.

In testimony that I claim the invention set forth above I have hereunto set my hand this 21st day of March, 1888.

JOSEPH T. BENDER.
